Attorney.

UNITED STATES PATENT OFFICE.

SAMUEL B. PEAKMAN, OF NEW YORK, N. Y.

SCREW-DRIVER.

SPECIFICATION forming part of Letters Patent No. 236,692, dated January 18, 1881.

Application filed August 23, 1880. (No model.)

To all whom it may concern:

Be it known that I, SAMUEL B. PEAKMAN, of New York, in the State of New York, have invented a new and useful Improvement in Screw-Drivers, of which the following is a specification.

The nature of my invention consists in constructing the screw-driver and the handle for the same bent in the desired shape out of one piece or rod of steel or iron.

In the accompanying drawings, Figure I represents a front view of my improved screw-driver. Fig. II is a section at line *x*, Fig. I.

I take a bar of steel of the required strength, and flatten one end, *b*, to form the required shape for a screw-driver. The bar is then bent around to form a convenient handle for the tool, as shown at *a a a*. The end *c* is slightly flattened and pointed at one side to lie against the side of the bar, and it is then fastened to the same.

The manner of fastening the end *c* to the side of the bar *a* may be done in various ways. The same may be soldered or riveted to the bar, or the end *c* may be tapered and twisted spirally around the bar *a*. I prefer for that purpose a ferrule, *n*, the opening at the lower

end of which is only of such a size as to allow the rod *a* to pass, while at its upper end the said opening or cavity is sufficiently large to insert the flattened and pointed end *c* as well as the rod *a*. This ferrule is placed upon the rod *a* after the end *b* has received the desired shape of a screw-driver. The rod *a* is then bent into the desired shape to form the handle, and its end *c* flattened and pointed, when, after said end *c* is laid close against the side of the rod *a*, this ferrule *n* is moved upward and passed partly over this end *c*, so as to confine the same.

I am aware that it is not new to form a cork-screw from a single piece of metal, and I make no claim thereto.

What I do claim is—

In combination with bar *a*, having beveled end *c* folded against it to form a handle for the screw-driver, the tapering ferrule *n*, binding said end *c* against the body of said bar, substantially as set forth.

SAMUEL B. PEAKMAN.
